UNITED STATES PATENT OFFICE.

GARRY W. MUNSON AND THOMAS F. HODGKISS, OF NEW YORK, N. Y.,
ASSIGNORS TO MUNSON SUPPLY COMPANY, OF NEW YORK, N. Y.,
A CORPORATION OF NEW YORK.

CUSHION-KEY FOR TYPE-WRITERS.

No. 832,617.

Specification of Letters Patent.

Patented Oct. 9, 1906.

Application filed June 1, 1906. Serial No. 319,798.

To all whom it may concern:

Be it known that we, GARRY W. MUNSON and THOMAS F. HODGKISS, citizens of the United States, residing at New York, in the county of New York and State of New York, have invented new and useful Improvements in Cushion-Keys for Type-Writers, of which the following is a specification.

This invention relates to certain new and useful improvements in cushion-keys for type-writers and other key-operated machines, and has to do particularly with the yielding finger-impact-receiving cushion-cap.

Heretofore in a general sense cushion attachments or appliances for keys of key-operated machines have been proposed, but they are interiorly hollow and depend altogether upon a so-called "air-cushion." Such prior devices do not completely and satisfactorily answer all the requirements and are particularly open to the objections that they yield excessively under finger impact in the operation of the machine, that after brief use the resiliency of what may be termed the "crown" or impact-receiver of the device is impaired and the crown assumes an undesirable cup-like or collapsed state, and that in the practical use of prior contrivances by reason of the manner of formation and connection thereof with the finger-key after comparatively brief use under intermittent finger impact the material of the cushion device is cut into by the medium which connects it to the finger-key, with the result that its usefulness is soon destroyed.

This invention has for its object to provide a thoroughly-efficient cushion-key or cushion attachment for keys so constructed and arranged and connected to the key of the instrument when in the form of an attachment that while obviating the objections existing to prior contrivances, as above mentioned, and as otherwise existing in said prior contrivances, provides a cushion finger-impact-receiving key, the crown of which is supported against excessive yielding, and, additionally, such a device in which means for supporting the finger-impact-receiving crown serves also to assist the inherent resiliency of such crown to maintain its initial and normal as contradistinguished from a collapsed condition.

The invention also has for its object to provide such a device in which the finger-impact-

receiving crown has a peripheral wall relatively stout as compared with the other portions of the cushion-cap whereby the practical yielding of the device under finger impact is in the crown, which is interiorly and centrally supported by means relatively less resistant than the peripheral wall

Finally, the invention has for its object to provide a cushion finger-impact-receiving cap for keys of key-operated machines so arranged and connected to the keys of the machine that its form is maintained against outward spreading and inward collapsing.

With the foregoing objects in view the invention consists in a device or attachment comprising the construction and possessing the features and advantages hereinbefore and hereinafter described, and then referred to in the appended claims. In this connection it is to be understood that the invention within its field is claimed in respect of its generic features and also additionally and as important items of invention in respect of the details referred to in the description and specifically referred to in some of the appended claims.

In the accompanying drawings, illustrating the invention, Figure 1 is a view showing a key of a key-operated machine in elevation with the device of this invention attached thereto and shown in vertical cross-section. Fig. 2 illustrates in perspective the members comprised in the cushion element of the device shown separated. Fig. 3 is a view similar to Fig. 1 of a different form or embodiment of the invention. Fig. 4 shows in perspective separated the members comprising the cushion element of the type of device shown in Fig. 3. Fig. 5 is a sectional view of another form of a device embodying the invention, and Fig. 6 is a perspective view of the same.

Premising that several types of the generic invention are shown in the drawings, of which types that illustrated in Figs. 1 and 2 is the preferred, the reference-numeral 1 designates the head of a key of a key-operated machine, such as a type-writer or the like, and 2 the stem.

The reference-numeral 3 designates generally the medium by which the cushion-cap is attached or connected to the key, and, as illustrated in the preferred example of the

invention, this is fashioned for connection to the head 1 of the machine-keys.

4 designates generally the cushion-cap. As shown, the attaching or connecting member 5 is formed of a tubular section 5, of metal, conforming in cross-sectional aspect to the size and cross-sectional characteristic of the key-head. This section of material has an open bottom and a closed top and is at its 10 closed end turned inwardly upon itself, as clearly shown in Figs. 1 and 3, to provide a diaphragm or seat 6, which rests upon the key-head 1, a chamber 7 to receive or fit over the key-head 1, and a socket 8, defined by a 15 marginal wall 9, in the illustrated example consisting of the double thickness of the section 5 to receive the cushion element 4. The cushion element, as shown, consists of a rubber cap comprising a crown 10, having a relatively stout depending peripheral supporting-wall 11, which rests upon the seat 6. This depending wall is reduced, and the upstanding wall 9 embraces and closely engages and braces the depending wall of the cushion element. 20 The reduction of the area of the depending wall of the cushion member results in a shoulder 11^a, which laps over the upper edge of the confining-wall 9.

The finger-impact-receiving crown 10 is 25 supported centrally for the purpose of preventing excessive yielding thereof and to avoid the objections hereinbefore referred to as existing in the prior devices. This is accomplished in the preferred form illustrated 30 in Figs. 1 and 2 by means of inner walls 12 of relatively less resistance or, conversely, of greater yielding quality than the peripheral wall 11, bridging across and connecting diametrically opposite points of said wall 11. 35 The inner or central supporting-walls 12, as shown, are relatively thinner than the peripheral supporting-wall 11 and are thus less resistive or of greater yielding capacity, and when they are formed integral with the 40 crown and the wall 11 they serve the further useful function of spreaders for the latter, connecting diametrically opposite portions of said wall, as it were, together and preventing the wall 11 in actual use from becoming 45 misshapen or falling down by otherwise possible inward canting thereof. The crossing crown-supporting walls 12 result in 50 pockets 13 interiorly of the cap, which pockets are filled by blocks of rubber 14, conforming to the size and shape of the pockets. The 55 blocks 14 are of softer rubber than that of which the cap proper is constructed, and they serve, together with the crown-supporting walls 12, to maintain the normal form of 60 the device in continued use thereof and resist to a desirably appreciable degree lateral flexure of the walls 12 under finger impact. The wall 9 of the socket in which the cushion-cap is arranged surrounds the peripheral wall 11 65 and hugs the same closely exteriorly, thus

affording firm and secure lateral support therefor, preventing the distortion or falling down of said walls by an outward canting thereof.

The cap 4 may be securely held in place in 70 the socket 8 and resting against the diaphragm-sear 6 by any suitable means, as by glue, and, if desired, this may be supplemented by burs 15, which penetrate the wall 11 of the cushion-cap. As thus organized the 75 cushion-cap has been found in practice thoroughly efficient, presenting a finger-impact receiver which while having the desired yielding or cushion quality is yet supported against excessive yielding or collapsing and 80 is so guarded and protected in its association with the machine-key that its normal form is maintained and its durability greatly increased. Each element serves a designed function, and they coöperate with each other 85 to provide an eminently satisfactory device. In actual normal use the relatively stout depending wall 11 sufficiently withstands the finger-pressure, the yielding or cushion quality of the device residing mainly in the crown 90 thereof, the degree of yielding of which is regulated by means of the supporting-walls 12 and the filler-blocks 14, of soft rubber, while inward canting of the depending wall 11 is prevented by the crown-supporting 95 walls 12 and the filler-blocks 14, and finally the cap is externally supported against distortion and disformation by means of the wall 9.

While that which has been described as 100 the preferred form is the one we recommend in practice, having been found thoroughly efficient and satisfactory, we do not desire to be understood as restricting the invention in some of its aspects to this particular form. 105 The results aimed at and attained may be secured, though perhaps in not so great a measure, if the soft-rubber filler-blocks are not utilized. Therefore in the broader view of our invention we recognize the possibility of 110 leaving these blocks out.

In Figs. 3 and 4 a different form of the generic invention is shown, in which form the crossing crown-supporting walls 12 and filler-blocks 14 are substituted by a single 115 soft-rubber filler-block 14^a, conforming in shape to and filling the interior cavity of the cap. This filler-block 14^a serves to support the crown 10 against excessive yielding and also to brace the depending walls 11 against 120 inward canting in use.

In Figs. 5 and 6 another form of the generic invention is shown, in which the finger-impact-receiving crown is supported by a centrally-disposed annular wall 12^a of less 125 resistance than the depending wall 11 of the crown. It is desirable and it is recommended that filler-blocks 14^b, Fig. 6, or sections of appropriate form and size be introduced into the space between the peripheral wall 11 130

and the annular wall 12^a and also in the cavity within said wall 12^a. This form of invention, like that illustrated in Figs. 3 and 4, is capable of attaining the generic result secured by the invention and is included within the scope of the claims appended hereto.

The forms of invention shown are considered to be the best known forms of securing the desirable results designed for the device, and that form shown in Figs. 1 and 2 is by us regarded as the preferable one. We wish it clearly understood, however, that within the broader aspects of the invention we do not limit ourselves to either of the forms shown, which in this respect may be regarded as illustrative merely.

Having thus described our invention, what we claim as new, and desire to secure by Letters Patent, is—

1. A cushion-key or key-cap comprising a yielding crown, a relatively stout peripheral supporting-wall and a yielding inner or central crown-support of relatively less resistance than said peripheral supporting-wall located opposite the finger-impact-receiving portion of the crown.

2. A cushion or key-cap comprising a yielding crown, a relatively stout peripheral supporting-wall, and a yielding inner or central crown-support consisting of a wall of relatively less resistance than said peripheral wall and formed integral with said crown and peripheral wall located opposite the finger-impact-receiving portion of the crown.

3. A cushion-key or key-cap comprising a yielding crown, a relatively stout peripheral supporting-wall, and a yielding inner or central crown-support consisting of walls of relatively less resistance than said peripheral wall and formed integral with said crown and peripheral wall and located opposite the finger-impact-receiving portion of the crown, and a support embracing said peripheral walls and coacting with the crown-supporting wall to maintain the operative position of said peripheral wall.

4. A cushion-key or key-cap comprising a yielding crown, a relatively stout peripheral supporting-wall and an inner or central crown-support consisting of walls formed integral with said crown and peripheral wall and bridging across between diametrically opposite points of the latter.

5. A cushion-key or key-cap comprising a yielding crown, a relatively stout peripheral supporting-wall, an inner or central crown-supporting wall of relatively less resistance than said peripheral wall, and filler-blocks of greater yielding quality than the material of

the key or cap, occupying the interior pockets within said crown.

6. The combination of an attaching member having a chamber to receive a key-head, a socket to receive a cushion-cap having a cap-supporting wall, and an intervening cushion-cap seat; and a cushion-cap comprising a yielding crown, a relatively stout peripheral supporting-wall disposed in said socket within said cap-supporting wall, and an inner or central crown-supporting wall of relatively less resistance than said peripheral wall.

7. The combination of an attaching member having a chamber to receive a key-head, a socket to receive a cushion-cap having a cap-supporting wall and an intervening cushion-cap seat; a cushion-cap comprising a yielding crown, a relatively stout peripheral supporting-wall disposed in said socket within said cap-supporting wall, an inner or central crown-support consisting of cross-walls formed integral with the crown-supporting, depending peripheral wall and connecting diametrically opposite portions of said wall; and filler-blocks occupying the pockets within said cap.

8. In a cushion-key for key-operated machines, a cushion-cap 4, having a crown 10, a relatively stout depending wall 11, and inner or central crown-supporting walls 12 relatively less resistant than wall 11, and a plurality of yielding filler-blocks 14 interposed between the crown 10 and seat 6.

9. In a cushion-key attachment for key-operated machines, a connecting mechanism 3 having a seat 6, chamber 7, socket 8, and wall 9, a cushion-cap 4 having a crown 10, a relatively stout depending wall 11 fitted in the socket 8 within wall 9, and inner or central crown-supporting walls 12 relatively less resistant than wall 11.

10. In a cushion-key attachment for key-operated machines, a connecting mechanism 3, having a seat 6, chamber 7, socket 8, and wall 9, a cushion-cap 4 having a crown 10, a relatively stout depending wall 11 fitted in the socket 8 within wall 9, inner or central crown-supporting walls 12 relatively less resistant than wall 11, and filler-blocks 14 interposed between the crown 10 and seat 6.

In testimony whereof we have hereunto set our hands in presence of two subscribing witnesses.
